Primary Examiner — Susan Moon Lee(57) **CLAIM**

The ornamental design for an adjustable height pet feeder, as shown and described.

DESCRIPTION

FIG. 1 is a left perspective view of an adjustable height pet feeder;

FIG. 2 is a right perspective view thereof;

FIG. 3 is a right, rear perspective view thereof;

FIG. 4 is a left, rear perspective view thereof;

FIG. 5 is a top view thereof;

FIG. 6 is a bottom view thereof;

FIG. 7 is a front view thereof;

FIG. 8 is a left side view thereof;

FIG. 9 is a right side view thereof; and,

FIG. 10 is a rear view thereof.

1 Claim, 7 Drawing Sheets---
